US0D1066622S

(12) **United States Design Patent** (10) Patent No.: **US D1,066,622 S**
(45) Date of Patent: ** *Mar. 11, 2025

(54) **STOVE**

(71) Applicant: **Huizhou Haorui Hardware Technology Co., Ltd**, Huizhou (CN)

(72) Inventors: **Yong Zhang**, Huizhou (CN); **Chaosen Wang**, Huizhou (CN)

(*) Notice: This patent is subject to a terminal disclaimer.

(**) Term: **15 Years**

(21) Appl. No.: **35/515,764**

(22) Filed: **Nov. 22, 2022**

(80) **Hague Agreement Data**

Int. Filing Date: **Nov. 22, 2022**

Int. Reg. No.: **DM/225150**

Int. Reg. Date: **Nov. 22, 2022**

Int. Reg. Pub. Date: **Dec. 9, 2022**

(51) **LOC (15) Cl.** 23-05

(52) **U.S. Cl.**

USPC **D23/343**

(58) **Field of Classification Search**

USPC D7/323, 331-335, 337-341, 346-347, D7/402, 405, 408-409; D23/317, 332, D23/335, 338-339, 342-343, 346-348, D23/350, 397, 402
